UNITED STATES PATENT OFFICE.

EDGAR M. SMITH, OF NEW YORK, N. Y.

DEVICE FOR PREVENTING CREEPING OF RAILWAY-RAILS.

No. 918,603.

Specification of Letters Patent. Patented April 20, 1909.

Application filed April 22, 1908. Serial No. 428,566.

To all whom it may concern:

Be it known that I, EDGAR M. SMITH, a citizen of the United States, residing at New York, county of New York, State of New York, have invented a certain new and useful Improvement in Devices for Preventing Creeping of Railway-Rails, and declare the following to be a full, clear, and exact description of the same, such as will enable others skilled in the art to which it pertains to make and use the same, reference being had to the accompanying drawings, which form a part of this specification.

My invention has for its object to provide a simple and novel device for preventing rails from creeping.

The various features of novelty whereby my invention is characterized will be herein-after pointed out with particularity in the claims, but for a full understanding of my invention and its object and advantages reference may be had to the following detailed description taken in connection with the accompanying drawing, wherein:

Figure 1 is a plan view of a preferred form of my invention showing a portion of a railway tie and in dotted lines a railway rail; Fig. 2 is an end view of the device shown in Fig. 1, the rail being shown in section; and Figs. 3 and 4 are views similar to Fig. 1 showing further modifications.

Referring to Figs. 1 and 2 of the drawing, A and B represent a pair of arms having upturned over-hanging flanges a and b at their outer ends. The members A and B are pivotally connected together at C. One of the members is continued beyond the pivotal point as at A' so as to provide an anchoring arm. The distances between the flanges a and b and the pivotal connection is such that when the device is placed beneath the base of a rail and the flanges a and b are made to engage with the sides thereof, the pivotal point will lie at one side of a line drawn transversely of the rail and passing through the flanges a and b. By this arrangement, if the anchoring arm is securely held then a tendency on the part of the rail to creep forwardly, that is in the direction from the pivotal point of the members toward their outer ends, will draw the two clamping jaws toward each other and into more intimate contact with the rail, in the manner that the weight of the block of ice causes the ice tongue to tighten their grip.

In applying the device, it is placed under

the base of the rail near and on the proper side of a tie D or other rigid support; the anchoring arm is pushed toward the rail until the jaws obtain a tight grip on the base 60 flange; and then a spike or other suitable fastening means is driven through an opening a' in the anchoring arm and into the tie.

The member B is preferably provided with a cam shoulder b² which is engaged by a heel a² on the member A adjacent the pivotal point. The pivotal connection is also preferably effected by means of a pin e carried by one of the members, as for example the member B, and passing through an elongated slot 70 a³ in the other member. This arrangement permits the device to be adjusted to different sized rails while at the same time affording a fulcrum for the heel a² at some point on the cam shoulder b².

In Fig. 3 the two clamping members E and F are shown as secured together by a simple pin and slot connection G. These members have jaws e and f, corresponding to the jaws a and b in the other form, at their outer ends. 80 The anchoring arm in this arrangement, instead of being a direct continuation of the member E extends rearwardly at an angle thereto so as to be more nearly parallel or in alinement with the member E. In this arrangement, therefore, the grip of the device upon the rail is tightened by pulling the anchoring arm away from the rail, the anchoring arm being then fastened to the tie as before by passing a spike or screw through an 90 opening e'.

In Fig. 4 I have shown an arrangement wherein the two clamping members H and I are connected together by means of a simple pivot joint J. h and i are flange-like jaws 95 similar to the jaws a and b in the first form. The anchoring arm H' extends from the member H in the same manner as the anchoring arm E does with respect to the member E. A secondary member I' extends 100 from the member I and is provided with a jaw i' which lies wholly or partly in the rear of the pivotal connection. It will be seen that in this arrangement the clamping jaws are prevented from being loosened by moving 105 the loose member rearwardly because the member I' serves as a stop. In the arrangement shown in Figs. 1 and 2 the dropping of the member B toward the rear is prevented by reason of the engagement of the heel and 110 cam shoulder together with the pin and slot connection.

It will now be seen that I have provided a simple device consisting of two parts fastened together by a simple pin or rivet, the device being of such a nature that it is impossible for a rail to creep because a creeping tendency is effectually counteracted by a tighter gripping action which is induced thereby.

While I have described in detail a few preferred forms of my invention I do not desire to be limited to the exact construction and arrangement of parts shown, since in its broader aspects my invention may take various other forms as will be evident from the terms employed in the definitions thereof constituting the appended claims.

Having now fully described my invention, what I claim as new and desire to secure by Letters Patent is:—

1. A device of the character described comprising a pair of jaws arranged to underlie the base of a rail and-pivoted together at

a point beneath the rail, and an anchoring arm extending rearwardly from one of said jaws.

2. In a device of the character described, a pair of pivotally connected members having rail-engaging jaws located in front of the pivot, and an anchoring arm extending from one of said members in the rear of the pivot.

3. In a device of the character described, a pair of pivotally connected members adapted to be arranged beneath the base of a rail in front of a tie, jaws arranged on the ends of said members in front of the pivotal point and shaped to grasp the edges of the rail base, and an anchoring arm extending from one of said members to the tie.

In testimony whereof, I sign this specification in the presence of two witnesses.

EDGAR M. SMITH.
